UNITED STATES PATENT OFFICE.

JAMES A. RADCLIFFE, OF NEW YORK, N. Y.

DESIGN FOR BACK OF PLAYING-CARDS.

No. 39,905.

Specification for Design.

Patented April 6, 1909.

Application filed January 11, 1909. Serial No. 471,812. Term of Patent 14 years.

To all whom it may concern:

Be it known that I, JAMES A. RADCLIFFE, a citizen of the United States, residing at New York city, in the county of New York and State of New York, have invented a new, original, and ornamental Design for the Backs of Playing-Cards, of which the following is a specification, reference being had to the accompanying drawing, forming part thereof.

The drawing represents the back of a playing card ornamented with a new and ornamental design representing a velour mat

or similar ornamental fabric with a fringe about the four sides arranged to substantially cover the entire border of the card between the fabric and the edge and shown with the warp and woof of fabric.

I claim:

The ornamental design for the back of a playing card, as shown and described.

JAMES A. RADCLIFFE.
